STAPLE DRIVING MACHINE

Fridolin Polzer, Lester L. Wheeler, and Roy E. Peterson, Norwalk, Conn., assignors to The E. H. Hotchkiss Company, Norwalk, Conn., a corporation of Connecticut

Application May 25, 1938, Serial No. 209,886

19 Claims. (Cl. 1—3)

This invention relates to new and useful improvements in staple driving machines.

An object of the invention is to provide a staple-driving machine of generally improved appearance.

Another object is to provide a staple driving machine including an arrangement whereby loading of the machine with staples may be easily and quickly accomplished from the front of the machine.

Another object is to provide a staple driving machine and improved construction of safety means preventing a second staple entering the raceway of the machine until after the first staple entering the raceway has been driven therefrom.

A further object is to provide a staple driving machine adapted for use either as a stapling machine or as a tacker.

Other objects and advantages will become apparent from a consideration of the following detailed description taken in connection with the accompanying drawings wherein satisfactory embodiments of the invention are shown. However, it is to be understood that the invention is not limited to the details disclosed but includes all such variations and modifications as fall within the scope of the invention and of the appended claims.

In the drawings:

Fig. 1 is a longitudinal sectional view through the complete machine;

Fig. 1a is a transverse section substantially on line 1a—1a of Fig. 1;

Fig. 2 is a sectional view as along the line 2—2 of Fig. 1 on a somewhat enlarged scale, but with the staple guide bar in projected position for loading of the same;

Fig. 3 is a view looking from the lower side of Fig. 2 but with the head of the machine shown in longitudinal section;

Fig. 4 is a sectional view taken as along the line 4—4 of Fig. 1;

Fig. 5 is a detailed side elevational view of the front portion of the staple guide bar showing the manner in which the same may be loaded from front end;

Fig. 6 is an end view looking into the guide bar as from the left in Fig. 5;

Fig. 7 is an enlarged sectional view showing the construction of the follower means of the machine;

Fig. 8 is a top plan view, also on an enlarged scale, of such follower means;

Fig. 9 is a top plan view showing the anvil which may be employed when the machine is used as a stapling machine;

Fig. 10 is a bottom plan view of the front portion of the base, the yielding foot piece or block being omitted whereby the manner in which the anvil is mounted may be better illustrated;

Fig. 11 is a sectional view as along the line 11—11 of Fig. 9;

Fig. 12 is the longitudinal sectional view through a modified construction of staple driving machine;

Fig. 13 is a sectional view as along the line 13—13 of Fig. 12 but with the staple guide bar projected as when it is to be loaded with staples;

Fig. 14 is a view looking from the lower side of Fig. 13 but with the head portion of the machine shown in section longitudinally of the machine;

Fig. 15 is a sectional view as along the line 15—15 of Fig. 12;

Fig. 16 is an enlarged detailed sectional view showing the relation of the guide bar to other portions of the head of the machine;

Fig. 17 is an enlarged transverse sectional view taken as along the line 17—17 of Fig. 12;

Fig. 18 is an elevational view of the forward portion of the guide bar of the machine and showing the manner in which such bar may be loaded from its front end;

Fig. 19 is an elevational view looking into the front end of the guide bar as it is illustrated in Fig. 18;

Fig. 20 is a front elevational view of the head of the machine;

Fig. 21 is a side elevational view of the forward portion of the head of the machine;

Fig. 22 is a front elevational view of a locking plate or member employed;

Fig. 23 is a front perspective view of the driver of the machine;

Fig. 24 is a front perspective view of a wear plate to be disposed over the driver;

Fig. 25 is a plan view of the rear end portion of the staple guide bar removed from the machine;

Fig. 26 is a vertical longitudinal section through the front lower portion of the housing of the machine similar to Fig. 1 and on an enlarged scale;

Fig. 27 is a similar section of the rear portion of the machine;

Fig. 28 is a section similar to the rear portion of Fig. 3 on a larger scale and showing the fol-

lower just before it reaches the limit of its forward movement when the staple guide is drawn forwardly;

Fig. 29 is a detail section of a portion of Fig. 1 showing the staple driving plunger in locked position;

Fig. 30 is a section on an enlarged scale similar to Fig. 4 but showing the position of the locking device when the plunger is in its upward movement after being fully depressed;

Fig. 31 is a side elevation of the rear end portion of the staple guide bar of Figs. 1, 2 and 3;

Fig. 32 is a longitudinal section on an enlarged scale substantially on line 32—32 of Fig. 9;

Fig. 33 is a transverse section on an enlarged scale substantially on line 33—33 of Fig. 10; and

Fig. 34 is an exploded view of the front portion of the housing of the form of device shown in Fig. 12 indicating how the inner housing may be removed from the outer housing.

Fig. 35 is a transverse section of a modified form of staple guide bar, and staple used therewith shown in elevation.

Referring in detail to the drawings, and at first more particularly to the form of the invention shown in Figs. 1 through 11, the machine as there disclosed comprises a main upper portion or body generally designated 10 and a base 11 with which said body is associated when the machine is being used as a stapling machine. The body 10 and base 11 are detachably connected whereby the former may readily be removed from the base and used as a tacker when desired.

Body 10 includes a sheet metal housing comprising a top wall portion 12 and side walls 13, the housing in transverse section being substantially of inverted U-shape. Located between the lower edge portions of housing walls 13 is an elongated tubular member 14 rectangular in transverse section as shown in Fig. 4. Member 14 may be welded or otherwise secured to the walls 13, and is preferably bent up of sheet metal and so arranged that its bottom wall 15 comprises the edge portions of the sheet from which it is bent, such edge portions being somewhat spaced apart to provide a channel 16 extending for the length of the member.

Member 14 extends from the rear wall 17 of the body housing to a point at the inner side of the raceway 18 (Fig. 1) of the machine. Within said member is a U-shaped staple guide bar 19 longitudinally movable in the member and provided on its underside with lugs 20, which may be pressed from the metal of the guide bar, and which are normally disposed in the channel 16 above referred to whereby movement of the guide bar relative to member 14 is limited and guided.

Extending through the guide bar 19 is a rod 21 the rear end of which is fixed to the housing wall 17 at 22 (Fig. 1) and said rod extends for substantially the entire length of the guide bar. About the rod is a coil spring 23 which functions to urge a follower 24 forwardly along the guide bar and feed staples forwardly to driving position. Such follower is of inverted U-shape and straddles the upper side of the guide bar whereby as it moves forwardly along the latter it will push staples along the guide bar toward the raceway 18. Follower 24 is provided in its top wall toward its forward end with an opening 25 (Figs. 7 and 8) immediately rearwardly of which is a strap-like portion 26 followed by an opening 27, the rear edge of which last opening is defined by the forward edge 28 of a depressed

portion 29 of the top wall leading to the rear end of the follower.

On the follower is a member 30 having an upstanding forward end 31 the rear side of which is curved or bevelled as at 32. The rear end of member 30 comprises a pair of spaced apart depending portions 33 straddling the rod 21 and against which the forward end of spring 23 presses. As clearly shown in Fig. 7 the member 30 includes a portion disposed on the depressed portion 29 of the top wall of the follower and a portion 34 located under the follower strap portion 26, while the upturned forward end 31 of the member projects through the opening 25 in the follower.

Obviously, the spring 23 pressing against the portions 33 of member 30 and the latter being mounted on the follower, the spring is constantly tending to move the follower forwardly along 20 the guide bar 19. It is also noted that the member 30 may rock on the follower about the edge 28 of the portion 29 of the latter whereby the upstanding forward end 31 of the member may move downwardly or inwardly with respect to the 25 follower. The purpose of this arrangement will later be fully set forth.

Mounted in the forward portion of the body 10 is an upright U-shaped member 35 (Figs. 1 and 2) which may be welded or otherwise secured 30 in place and which receives and acts as a guide for a plunger 36. Such plunger is vertically movable and is normally held in the elevated or retracted position of Fig. 1 by coil spring 37. At its forward side plunger 36 is provided with a 35 lug 38 entering an opening in a driver plate 39 located between the plunger and the connecting portion 40 of the U-shaped member 35. With this arrangement as the plunger is moved the driver is carried with it, and as the plunger is depressed the lower portion of the driver is moved downwardly through the raceway or guideway 18 to drive a staple therethrough. Lugs 41 (Figs. 2, 4 and 30) struck up from the side arm portion of U-shaped member 35 prevent movement of 45 the plunger and driver in a direction away from wall 40.

At its upper end plunger 36 includes a roller 42 bearing against a wear plate 43 at the inner-side of an operating member 44. Such operating 50 member is adapted to be depressed by pressure of the hand and is located between the upper forward portions of the housing side wall 13, and in its normal or upwards position forms a continuation of the top wall 12 of the housing. The 55 operating member is somewhat in form of an inverted U when viewed in cross section and includes depending side portions 45 entering between the housing side walls 13, and at their rear ends such depending portions 45 are notched at 46 to receive an inturned flange 47 at the forward edge of housing wall 12.

Attached to the housing top wall 12, as by a rivet 48, is a flat spring 49 projecting forwardly beyond the flange 47 and pressing against a plate-like member 50 carried by the operating member 44. With this arrangement the spring 49 maintains the notches 46 in position receiving the flange 47 and the spring has some tendency to return the operating member to retracted position when depressed, but for the accomplishment of this function it is the spring 37 which is relied upon. Toward their forward ends side portions 45 carry inturned lugs 51 (Figs. 1 and 4) which engage under shoulders 75

52 of the plunger whereby the operating member is secured to the plunger in such manner as not to have any appreciable movement independent of the plunger.

Attached to the forward end portion of the guide bar 19 is a U-shaped piece 53 the bottom or connecting wall 53a of which is secured against the outer side of the corresponding wall of the guide bar, and the side arms 54 of which are spaced from the side arms of the guide bar (see Figs. 2 and 6) in a manner to permit of the passage of the legs of staples. A U-shaped spring 55 has on the ends of its side arms inwardly bent ears 55a to enter openings 56 in the arms 54 of member 53 whereby such spring is susceptible of pivotal movement relative to the member 53.

Secured to the connecting portion of spring 55 as by rivets 57 is a plate 58 which when the spring is in a position of Figs. 1 and 2 is located opposite the forward end of guide bar 19 and so forms in effect a continuation of the wall 40 and defines the forward side of the raceway 18. Since this plate 58 is held in place by the spring 55 only, it will be understood that should an oversized staple or staple of a thicker wire enter the raceway the spring will yield to permit the plate 58 to move outwardly from normal position under action of the staple to permit of such oversized staple being forced through the raceway by the driver 39. The spring 55 is bent inwardly at 55b to permit this.

Notches 59 (Figs. 1, 26 and 31), are formed in the upper edges of the side walls of the guidebar adjacent the rear end thereof, and normally the lower end portion of a pawl 60 enters such notches whereby to hold the guide bar in place in its normal position of Fig. 1 within the housing. Pawl 60 is pivoted intermediate its ends at 61 and toward its forward end carries a button 62 projecting through an opening in the housing top wall 12. A coil spring 63 engages the pawl and normally maintains it in the position of Fig. 1 wherein the pawl is functioning to maintain the guide bar in a retracted position with its forward end so located that the raceway 18 is aligned with the driver 39.

When a supply of staples on the guide bar has been exhausted the operator depresses button 62 so as to rock the pawl 60 into a position removing its lower end from the notches 59 in the guide bar. Thereupon the spring 23 acting through the follower 24 causes the entire guide bar to move forwardly, because when there are staples on the guide bar they are pressed against the front wall 58 by the follower 24 under action of spring 23, and when there are no staples on the bar the forward end of follower 24 presses against the wall 58, and the operator may grasp the spring 55 and draw the guide bar out to the position of Figs. 2 and 3.

As the guide bar is being drawn outwardly through the front end of member 14, the upturned toenike portion 31 of the member 30 is riding against the undersurface of the top wall of member 14 and such member 30 is slightly tilted as in the dotted line position of Fig. 1 and full line positions of Figs. 26 and 28. Adjacent its front end the top wall of member 14 is provided with an opening 66 (Figs. 1, 3, 26 and 28), the front edge of which is flat while its rear edge 66a may be curved or tapered as shown. Therefore, as the guide bar reaches its fully extended position, the follower 24 also reaches a position

where the portion 31 moves into the opening 66 (see Fig. 3 and dotted lines Fig. 28) and coming against the forward edge of such opening cannot move further and thus forms a stop to limit forward movement of the guide bar 19 and prevent its being drawn clear from the housing as the shoulders 19a (Figs. 28 and 31). Also shown in Figs. 1 and 3 the top edges of guide bar 19 engage the rear end of the follower 24. The spring 23 bearing against the portions 33 is constantly trying to rock the member 30 into the position of Figs. 3 and 7. The guide bar being thus exposed, staples may be dropped vertically onto it in positions straddling it. In Fig. 3 the staples 64 are about to be dropped onto the guide bar as suggested by arrow 64a. Should the staples be somewhat bent or out of alignment so as to be of such shape that they cannot be readily dropped over the guide bar, then the spring 55 may be swung up to the full line positions of Figs. 5 and 6 (such position shown in dotted lines in Fig. 3) whereupon the staples 65 may be moved onto the guide bar over the front end thereof as suggested by the arrow 65a in Fig. 5.

The guide bar having been loaded with staples (and the spring 55 having been returned to the full line position of Fig. 2 if it has been moved from such position) the guide bar is pushed back into the member 14, and when it reaches the proper position the spring 63 will influence the pawl 60 to rock it to the position of Fig. 1 securing the guide bar in such proper position. The U-shaped piece 53 at the forward end of the guide bar may be provided with a lug 67 to enter the forward end of the channel 16 in order to insure along with the lugs 20 that the guide bar is in proper alignment within the member 14.

The guide bar being back in position, operating member or hand piece 44 may be depressed to move driver 39 through the raceway to drive a staple therefrom, it being understood that the follower 24 is constantly urging the staples along the guide bar toward such raceway. Means are provided to prevent a second staple from entering the raceway until after the first staple to enter it has been driven from it. This means, as here disclosed, includes a pawl 68 (Figs. 1 and 4) loosely pivoted on a rod 69 about which is coiled a portion of a spring having an arm 70 bearing against a base plate 71 and having an arm 72 engaging the pawl. The tendency of the spring acting through its arm 72 is to press the pawl against the rear wall of the plunger 36. Such rear wall has an opening 73 adjacent which is a projection or cam 74 having a flat inclined side 76 and a curved side 77.

As the plunger moves downwardly the opening 73 comes opposite the hooked end of pawl 68 and the spring tends to move such pawl end into the opening. Should the plunger be driven only a portion of a stroke the driver will carry a staple only part way through the raceway 18. If the operating member 44 is then released, as the pawl 68 has remained in alignment with the opening 73 its upper hooked end will engage the lower edge of the opening 73 as shown in Fig. 29 and prevent complete retraction of the plunger and driver so that the lower end of the driver will remain partly across the forward end of the guide bar and prevent a second staple entering the raceway.

If the plunger is moved downward to its lowest position the hooked upper end of the pawl 68

moves along the left hand side 76 of cam 74 (as shown in Fig. 15) and is swung somewhat to the left tensioning the spring 72. When the plunger reaches its lowermost position, which is its position when the driving of the staple is completed, the upper end of cam 74 is below the hook of the pawl. The tensioned spring 72 then swings the upper hooked end of the pawl to the right to carry the hook over the curved right hand side 77 of the cam, and which is the position shown in Fig. 30. Therefore, as the plunger starts its return movement the surface 77 of the cam moves under the hooked end of the pawl and moves it to the right thus keeping such end away from the opening 73 so that it cannot engage the lower edge of this opening to thus stop upward movement of the plunger. The plunger, therefore, is allowed to complete its return or upward movement, whereupon the lower end of surface 77 moving past the pawl, the latter returns to the normal position of Figs. 1 and 4. The pawl 68 may be a spring member to permit the hooked upper end to have this lateral movement and to return it to the normal position after the hook passes the lower end of the cam.

In short the left hand side 76 of cam 74 keeps the hook of the pawl in alignment with the opening 73 in the plunger until the plunger reaches its lowermost position to complete driving of the staple. Therefore if the plunger is released before it is operated to this position the hook on the pawl will engage the lower edge of opening 73 as the plunger moves upwardly and prevents its moving to its fully retracted or normal upper position. On the other hand if the plunger is operated to its lowermost position the upper end of cam 74 is below the hook of the pawl and this hook is swung to the right by spring 72 to a position over and in alignment with the right hand side 77 of the cam. Then as the plunger rises this wall 77 shifts the hook to the right out of alignment with the lower edge of opening 73 so that it cannot engage this edge to arrest upward movement of the plunger, and the plunger is permitted to move to its uppermost or normal position.

As above suggested, when the machine is to be used as a stapling machine the body 10 and the parts carried thereby are mounted on the base 11. Such base includes an elongated body 78 which may be formed of sheet metal, and it is open in its upper side toward its rear end and at each side of such opening is provided with upstanding ears 79. Such ears carry a pin 80 (Figs. 1, 1a and 27) spanning the opening. Secured to the base 55 body as by means 81 is a flat spring 82 having an end portion 83 protruding through such opening so as to be disposed between the ears 79.

Welded or otherwise secured to the underside of the member 14 (Figs. 1, 1a and 27) adjacent to the rear thereof is a housing mounting means comprising an inverted U-shaped member including a connecting portion 84 and a pair of side arms or portions 85. Arms 85 are each provided with a bayonet slot 86 and are so spaced apart as to be receivable between the ears 79. When the housing is to be mounted on the base the open ends of the slots 86 are aligned with the pin 80 and at such time the lower edges of the arms 85 are in engagement with the projecting end of the spring 83. Then the whole rear portion of the housing is forced downwardly and the housing shifted forwardly to locate the pin 80 in the closed end portions of the slots 86. This is as shown in Figs. 1 and 27 and the spring 82 is ten-

sioned maintaining the housing on the base, and the spring also normally maintains the forward portion of the housing spaced above an anvil 87 by pressing on the lug 85a or the edges of arms 5 85 forwardly of the pivot pin 80.

The forward portion of base 11 is bowed or crowned and includes an intermediate portion 88 (Figs. 1, 9, 10 and 11) which is depressed and between its ends provided with transverse channels or grooves 89 (Fig. 1). At opposite sides of such portion are slots which may be described as arranged in two pairs designated 90 and 91 (Fig. 10). The anvil 87 carries leg-like portions 92 (Fig. 33) projecting downwardly through the 15 slots 91. Also, the anvil carries legs 93 projecting through the slots 90 and such legs 93 include forwardly directed portions 94 (Figs. 1 and 10) spaced from the wall of the base and somewhat hook-shaped.

20 Located at the underside of the base is a spring 95 having end portions 96 received by the hook-like arm portions 94 and such spring includes forwardly and rearwardly directed arms 97 and 98 (Figs. 1, 9 and 10) which, as shown best in 25 Fig. 1, bear against the underside of the base. The tendency of this spring is to hold the anvil 87 down against the depressed base portion 88. In its upper surface the anvil is provided with permanent clinching recesses 99 arranged to bend 30 both prongs of the staple inwardly toward each other and with recesses 100 and 100a the latter to be used when a staple is to be employed as a temporary fastener, the recess 100 bending one prong inwardly and the recess 100a bending the 35 other prong in the same direction or outwardly. The formation of these recesses is accomplished in a manner to provide depressed portions 101 at the lower side of the anvil.

When such depressed portions are in the rear 40 pair of the grooves 89 the anvil is so located that the permanent fastening recesses 99 are in alignment with the raceway 18 and when the anvil is slid forwardly to have the projections 101 in the forward and intermediate groove 89 the temporary fastener clinching recesses 100 and 100a 45 are in alignment with the raceway. The spring 95 keeps the anvil against the base portion 88 so as to retain the interlocking engagement between these parts, but it will be apparent that it is not 50 a positive but only a frictional action. Therefore, the anvil may be manually shifted to one position or the other as desired, the spring moving with the anvil but bearing at the ends of its arms 97 and 98 against the underside of the base 55 so that the projections at the underside of the anvil are snapped into the grooves 89. The movement of the anvil is guided by the portions of the base immediately at the sides of the depressed portion 88 and also to the location of the legs 92 and 93 in the slots 91 and 90.

At the rear end of the base there is secured a rubber cushioning block 102 and a somewhat similar but larger block 103 is located at the under side of the forward end of the base. Block 103 is 60 provided with openings which receive leg-like portions 104 welded or otherwise secured to the under side of the base at 105. This block 103 is hollow at its upper side as shown in Figs. 1 and 11 and so does not interfere with movement of the spring 95 or of the legs 92 and 93 of the anvil. As here shown the latter toward its rear end is provided with lateral enlargements 106 which may be manually engaged when shifting the anvil from one position to the other.

75 It will be noted the top surface of anvil 87 is

convexly curved in a plane transverse to the plane of the staple being driven. This insures that the papers or articles being stapled are gripped between the top surface of the anvil and the bottom of the upper body 10 at the plane of the staple so that they are properly and closely held together at the point where the staple is being driven.

Referring now to the form of the invention shown in Figs. 12 through 25, the same comprises 10 a body generally designated 107 and which may be used alone as a tacker or which may be detachably connected with the base 11 by means of the pin 80 and bayonet slot 86 the same as previously described in connection with the form of 15 Fig. 1. The body 107 includes a housing formed of sheet metal and comprising a top wall 108 and side walls 109 between which is located a transversely U-shaped sheet metal frame including side walls 110 and a bottom wall 112 which latter 20 rests on the bottom wall 113 of the outer housing. This bottom wall 113 may be brazed, soldered or welded to the side walls of the housing. Resting on said bottom or connecting wall 112 is a staple magazine and guide bar generally designated 114 (Figs. 12 and 14) and including an inner staple guide bar 115 and outer U-shaped or channel bar 116 (Figs. 13, 14 and 17) located one within the other. Such channel bars have their bottom walls or connecting portions secured together as by rivets 117 while their side portions are spaced apart to provide channels 118 (Figs. 13 and 19) for the accommodation of the legs of staples placed on and straddling the inner channel bar 115.

Straddling the inner channel bar 115 of the guide bar is a follower 119 formed of sheet metal and of inverted U-shape, and to the rear portion of which (by any suitable means such as a bent up ear 119a) is connected an end 120 of a flat 40 coiled spring 121 while the other end of such spring is fixed to a bar 122. The spring is constantly tending to coil about the bar 122 and thus is constantly tending to draw the follower forwardly along the guide bar in a manner to urge the staples 123 therealong, whereby to deliver the staples to a raceway 124 at the forward end of the guide bar.

On the forward end of the guide bar is a U-shaped member generally designated 125 and including a front plate or connection portion 126 and side arm portions 127 which latter have on their free end portions ears 127a inturned and disposed in openings 128 in the outer channel member 116 of the guide bar. With this 50 construction the member 125 may be swung from the full line position of Fig. 14 to the dotted line position of that figure, or to the full line position of Figs. 18 and 19. The purpose of this arrangement will later be set forth. Here it is noted that the plate 126 forms the forward side of the raceway 124 and that the bent in ends 127a of the arms 127 do not have a tight fit in the holes 128 but have limited movement therein in a direction longitudinally of the guide bar 114. Therefore the entire member 125 may yield forwardly as suggested in Figs. 13 and 14 when a staple of larger diameter wire is being driven through the raceway, this however being held in the normal position by the spring plate 143 as 70 will be later described.

In the forward portion of the housing there is arranged a plunger 129 having on its forward side a lug 130 projecting through an opening 131 in a driver plate 132 and also into an open-

5 ing 133 in a wear plate 134. A closure 135 is disposed over the front end of the housing and includes flange-like side portions 136 which embrace the housing side walls 109. Such side walls include forwardly projecting perforated ears 137 (Figs. 13 and 20) and the closure 135 includes a forwardly projecting portion 138 through the sides 139 of which pass a pin 140 which pin also passes through the ears 137 whereby the closure is secured in place. The front edges of the sides 140 of the inner frame have similar ears 137a at the inner sides of the ears 137 through which the pin 140 also passes.

A slot 141 (Fig. 20) opens through the upper end of the closure 135 and the lower end of the closure is substantially cut away providing an opening 142. Opening 142 aligns with the forward end of the guide bar 114 and when the latter is in normal position within the housing the lower end 143 of a spring locking plate 144 is extending across and in engagement with the connecting portion 126 of the U-shaped member 125 and yieldingly holds this member in proper position to form the front wall of the raceway 124 to help guide the staple being driven. Such locking plate is located between the front wall of the closure 135 and the wear plate 134 as shown in Fig. 12 and when in its lower position as in Figs. 12 and 20 its lower end portion 143 extends under the lower end of plate 134 so as to engage the front wall of member 125 as shown in Fig. 16, and serves to hold the guide bar within the housing as well as hold member 125 in normal staple guiding position.

35 At its upper end the locking plate 144 includes a relatively thin or narrow neck-like portion 145 projecting through the open ended slot 141 in the upper end of cover 135 and beyond such cover the neck-like portion carries a hand piece 146 which may, if desired, be moulded to said portion. The plunger 129 together with the driver 132 and the plate 134 are vertically movable at the inner side of the locking plate and the plunger is guided in its movements between the side walls 110 of the inner frame and between the locking plate 144 and the inturned ends or flanges 147 (Fig. 13) of plates 148 which may be welded or otherwise secured to the frame sides 110. The slideable locking plate 144 is cut away on its opposite side edges as shown at 144a (Fig. 22) to form clearance for ears 137 and 137a and the shoulders 144b formed at the lower ends of these notches engage the ears to limit the upward movement of the plate. Associated with the plunger is a safety means comprising the pawl 68 and the spring 72 and associated parts functioning as and for the purpose described in connection with the first form of the invention.

A hand operating member 149 includes side flanges 150 which enter between the housing walls 109, and a pin 151 passing through said flanges and the upper portion of plunger 129 secures the operating member to the latter. The inner or rear end portion 152 (Fig. 12) of the operating member is disposed under the forward edge portion of the housing top wall 108 and such operating member closes the space between the upper edges of the forward portion of the side walls 109 of the housing. A coil spring 153 serves to return the plunger and the operating member 149 to their normal or retracted positions after they have been depressed to have driver 132 drive a staple through the raceway 124.

When the machine is to be reloaded with 75 staples the locking plate 144 is moved upwardly

so as to position its lower end portion 143 above the opening 142 as shown in Fig. 14 whereupon the guide bar and magazine 114 may be drawn outwardly to the position of Figs. 13 and 14. A screw 154 secured to the rear end of the guide bar 114 passes through a slot 155 (Fig. 25) in a plate 156 and has anchored to it one end of a small coil spring 157, the other end of which is anchored to a lug 158 at the forward end of said plate 156. At the rear end of the plate there is an upturned portion 159, and when the guide bar is within the housing such end 159 bears against the rear wall 160 of the housing (Fig. 12) whereby the forward end of the plate is moved forwardly with respect to screw 154 thereby by tensioning spring 157. With this arrangement as soon as the locking plate 144 is elevated as above described to release the guide bar 114, plate 156 actuated by spring 157 will function as a kicker to move the guide bar outwardly of the housing a sufficient distance where it may be grasped and pulled out to its fully extended position for loading the staple strip into it.

Thus the operator by grasping the forward end of the guide bar may draw it forwardly to the positions shown in Figs. 13 and 14. Thereafter staples 161 may be moved downwardly on to the guide bar as suggested by arrow 161a, Fig. 14, so as to have the staples straddle the inner channel member 115. If for any reason the staples may not be so applied, the front member 125 on the end of the guide bar is swung upwardly as in Figs. 18 and 19 and then the strip 162 of staples is moved onto the channel member 115 from the end thereof as suggested by arrow 162a in Fig. 18. This may be used for straight staples, as sometimes people who have gotten used to sliding the staple strip on to the staple guide bar from the end wish to continue to do so, or this end loading permits the use of a guide bar and staples in which the staple strip cannot be placed on the bar from the top, such for example as staples in which instead of the legs being parallel they are inclined inwardly as shown at 167 in Fig. 35 and the sides 168 of the guide bar 169 are tapered inwardly and downwardly in the manner disclosed in the patent to Vogel, No. 2,016,466, issued Oct. 8, 1935.

When the guide bar reaches the desired outermost position the screw 154 as shown in Fig. 14 comes against the inner end of the follower 119 so that the guide bar may not be drawn entirely out of the housing, and outward movement of the follower is limited since the end 120 of the spring 121 is attached to the follower and the spring passes over a plate 163 as shown best in Fig. 14. After the guide bar is loaded with staples it is pressed back into the housing again tensioning spring 157, and thereafter the locking plate 144 is pushed down to the locking position of Figs. 12 and 20. Portions 164 are lanced from the side walls 110 of the inner frame and pressed over, as best shown in Fig. 17, so as to overlie the upper edge of the guide bar, and particularly the channel 118 thereof, whereby to prevent any upward movement of the staples off the guide bar. The upper edge of the opening resulting from the formation of these flanges or portions 164 is shown at 164a.

Projecting from the lower side of the guide bar at the forward end thereof is a lug 165 (Fig. 18) which may comprise the head of the screw 166 (Fig. 16), and the forward end of the bottom wall 112 of the inner frame is notched at 167 to receive such lug whereby when the guide

bar is in normal position it is additionally held against any lateral movement.

When the cover member 135 has been removed the entire inner frame 110 of the machine, including the guide bar and plunger means, as a unit with such frame, may be drawn outwardly through the forward end of the housing so as to better expose the various parts for repairs. The beginning of such movement is suggested by the dotted lines at the left in Fig. 12.

The same form of shiftable anvil 87 to give permanent or temporary setting of the staples may be used in the form of Figs. 12 to 25 the same as in the form of Figs. 1 to 11. In order to reassemble the parts in the housing it is but necessary to push the frame and parts carried thereby back into the housing and to then apply driver 132 and plate 134 against the front side of the plunger, position the locking plate 144 and the cover 135 and then insert the pin 140.

Having thus set forth the nature of our invention, what we claim is:

1. A staple driving machine including a housing, a staple driver for driving the staples, a staple guide bar for carrying staples to said driver and normally enclosed in said housing, said guide bar being longitudinally shiftable to and from an exposed position to permit of loading of the bar while in said exposed position, means for feeding the staples along the guide bar to driving position under the driver, and releasable means normally securing the bar in its enclosed position.

2. In a staple driving machine, a housing, a staple guide bar, a raceway at the forward end of the guide bar to which staples are to be fed from said guide bar, means for driving staples through said raceway, said housing enclosing said guide bar, said guide bar being longitudinally movable with respect to said enclosing housing whereby the guide bar may be withdrawn from the enclosing housing for loading, and releasable means normally securing the guide bar within the enclosing housing.

3. In a staple driving machine, a housing, a staple guide bar in said housing, a raceway, a follower for moving staples along said guide bar to said raceway, means for driving staples through said raceway, said guide bar being longitudinally movable to a position projecting from said housing and in which position staples may be placed on the guide bar, and means normally locking the guide bar in position within the housing.

4. In a staple driving machine, a housing including side walls, an elongated tubular member in the lower portion of said housing between said side walls, a staple guide bar normally within said member but withdrawable therefrom for loading, said member including an upper wall preventing upward movement of staples off the guide bar while the latter is in normal position, said guide bar having a shoulder, a pawl, spring means maintaining said pawl in position engaging said shoulder whereby to secure said guide bar in its normal position, and means operable from the outer side of said housing to shift said pawl against the action of said spring to release the guide bar.

5. In a staple driving machine, a housing including side walls, an elongated tubular member in the lower portion of said housing between said walls, a staple guide bar normally within said member but longitudinally movable through the forward end thereof to a loading position, a spring actuated follower on said guide bar for

urging staples therealong toward the forward end thereof, means normally retaining the guide bar within said tubular member and manually releasable to permit movement of the bar to the loading position, means providing a stop shoulder adjacent the forward end of said member, and means on said follower engageable with said stop shoulder when the follower reaches a forward-most position whereby to prevent the follower moving out of the member as the guide bar is being moved through the forward end thereof to the loading position.

6. In a staple driving machine, an elongated tubular member, a staple guide bar normally within said member but longitudinally movable through the forward end thereof for loading, manually releasable means for retaining said guide bar in normal position, and cooperating positioning means between said member and guide bar and comprising a channel in one and a projection on the other whereby to insure proper positioning of the guide bar within the member.

7. In a staple driving machine, an elongated tubular member, a staple guide bar normally within said member but movable through the forward end thereof for loading, a follower on said guide bar, a spring normally urging the follower along the guide bar toward the forward end thereof, manually releasable means normally retaining the guide bar within the member, said tubular member having an opening in its upper wall providing a shoulder adjacent its forward end, said follower including an element mounted on the follower body for movement relative thereto, said means including a projecting portion, said spring normally engaging said element for moving the follower along the guide bar and maintaining the projecting portion of the element against the upper side of the tubular member whereby as the follower reaches the forward end of the tubular member the action of the spring on said element shifts the same to cause the projecting portion thereof to enter said opening in the top wall of the member to prevent movement of the follower out of said member.

8. In a staple driving machine, a staple guide bar, a raceway to which staples are to be fed from said guide bar, means for driving staples through said raceway, a housing normally enclosing said guide bar and staple driving means, said guide bar being movable longitudinally through the forward end of said housing to expose a portion of the guide bar whereby the latter may be loaded with staples, manually shiftable means normally securing the guide bar within the housing, means on the forward end of the guide bar and carried thereby and cooperating therewith to form a wall of said raceway, and said means being yieldably secured to said guide bar whereby to be capable of movement outwardly with respect thereto to permit of an oversized staple being driven through said raceway.

9. In a staple driving machine, a staple guide bar, a raceway to which staples are fed from said guide bar, means for driving staples through said raceway, a housing normally enclosing said guide bar and staple driving means, said guide bar being movable through the forward end of said housing to an outer position, manually shiftable means normally securing the guide bar within the housing, means carried on the forward end of the guide bar and cooperating therewith when the guide bar is in normal position to form

5 the forward wall of said raceway, and pivots mounting said means on the guide bar whereby when the latter is in an outer position the means may be shifted relative to the guide bar to clear the end thereof to permit of the loading of the guide bar by the movement of staples on to the same in the forward end thereof.

10. In a staple driving machine, a housing, said housing having a raceway therein, means in said housing for feeding staples to said raceway, means in said housing for driving staples through said raceway, a base, an anvil on the forward portion of said base, said base having an opening in the upper side thereof toward its rear end, a spring secured to the base and projecting above said opening, an upstanding ear on the base at each side of said opening, a pair of depending ears on the lower side of said housing adjacent the rear end thereof, cooperating means on the ears of the base and the ears on the housing whereby the housing may be readily mounted on or removed from the base, said cooperating means comprising a cross pin carried by one of said pairs of ears and bayonet slots in the other pair of ears for receiving said pin, and said spring serving when the housing is on the base to yieldingly maintain the parts in relation with said pin in the closed end portions of said slots.

11. In a staple driving machine, a housing, a staple driving plunger in the housing, a staple guide bar within the housing to supply staples to the plunger and mounted for sliding movement in the housing, means for feeding staples 30 along the guide bar to a position to be driven by the plunger, said housing having an opening in an end thereof and through which the guide bar may be projected for loading, means normally holding the guide bar within said housing, and 35 means preventing complete withdrawal of the guide bar from the housing when the guide bar is projected for loading.

12. In a staple driving machine, a housing, said housing having a raceway therein, means in 45 the housing for feeding staples to the raceway, means in the housing for driving staples through the raceway, a base having a top wall portion convexly curved in a direction transversely of the plane of the staple, an anvil mounted on 50 said curved portion and provided with two sets of recesses to cooperate with the driving means for permanent and temporary setting of the staples, said anvil being convexly curved similarly to the curvature of the base and being 55 slideable thereon to bring either set of recesses into alignment with the driving means, and means for retaining the anvil in the different positions.

13. In a staple driving machine, a housing, a staple guide bar within said housing, said housing having an opening in an end thereof and through which said guide bar may be partially withdrawn for loading, a movable locking plate normally closing said opening and maintaining the guide bar within the housing, and means at 60 the outer side of said housing and operable to shift said plate to permit of movement of the guide bar through said opening.

14. In a staple driving machine, a housing, a staple guide bar within said housing, said housing having an opening in the forward end thereof and through which said guide bar may be partially withdrawn for loading, a slideable locking plate on the forward end of said housing and normally closing said opening and maintaining 65 the guide bar within the housing, means at the

outer side of said housing and operable to shift said plate to expose said opening, and a spring actuated kicker means on said guide bar and normally urging the same toward said opening whereby as said plate is shifted to expose the opening the bar is partially projected through the latter by the kicker means.

15. In a staple driving machine, a housing, a staple guide bar within said housing, said housing having an opening in the forward end thereof and through which said guide bar may be partially withdrawn for loading, a slidable locking plate on the forward end of said housing and normally closing said opening and maintaining the guide bar within the housing, means at the outer side of said housing and operable to shift said plate to expose said opening, kicker means associated with said guide bar and normally urging the same toward said opening whereby as the latter is exposed on movement of said plate the guide bar is partially projected through the opening, said kicker means comprising a slotted plate having an end bearing against the rear wall of said housing, a stud secured to the guide bar and projecting through the slot of the plate, and a coil spring anchored at its forward end to the forward end of said plate and at its rear end to said stud whereby the spring is tensioned while the guide bar is within the housing.

16. In a staple driving machine, a housing, a frame within the housing, a guide bar in said frame, means defining a raceway at the forward end of said guide bar, follower means on the guide bar for moving staples therealong toward said raceway, means on said frame and operable to drive staples through said raceway, said housing including a cover-like front wall, means removably securing said front wall to the housing, and said frame and all parts carried thereby being slidable out of said housing through the forward end thereof on removal of said front wall.

17. In a staple driving machine, a housing, a frame within the housing, a guide bar in said frame, means defining a raceway at the forward end of said guide bar, follower means on the guide bar for moving staples therealong toward said raceway, means on said frame and operable

5 to drive staples through said raceway, said frame including side wall portions, and flanges lanced and pressed from said side wall portions and disposed to extend partly over the upper side of said guide bar whereby to prevent upward movement of the staples thereon.

18. In a staple driving machine, a housing having a raceway therein, a staple guide bar within said housing, means for moving staples along said bar to said raceway, said housing having an opening in the forward end thereof and through which said guide bar may be partly withdrawn for loading, a locking plate having a resilient yieldable portion normally closing said 15 opening and maintaining the guide bar within the housing, means for shifting said plate to expose said opening, means at the forward end of said guide bar and normally forming a side of said raceway and bearing against said locking plate, and means connecting said means with the guide bar in a manner to permit of limited outward movement of said means away from the end of the guide bar whereby to permit of an oversized staple being driven through said raceway.

19. In a staple driving machine, a housing having a raceway therein, a staple guide bar within said housing, means for moving staples along said bar to said raceway, said housing having an opening in the forward end thereof and through which said guide bar may be partly withdrawn for loading, a locking plate having a resilient yieldable portion normally closing said opening and maintaining the guide bar within the housing, means for shifting said plate to expose said opening, a guide member pivoted to the forward end of said guide bar and normally forming the forward wall of said raceway, said guide member being mounted on the guide bar for limited movement away from the end of the bar, and said locking plate when in closing position backing up said guide member to retain it in normal position and permit it to move outwardly to allow staples of thicker wire to pass through the raceway.
